[57] CLAIM

The ornamental design for combined carrying bag and radio, as shown and described.

DESCRIPTION

FIG. 1 is a top, front and left side perspective view of a combined carrying bag and radio showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and

FIG. 7 is a right side elevational view thereof.

The strap portion in FIGS. 1 and 2 is broken away for clarity of illustration.

The strap portion in FIGS. 3, 5, 6 and 7 is broken away for ease of illustration.

FIG.2
